UNITED STATES PATENT OFFICE

CYRUS T. SCHIRMER, OF NEWTON, MASSACHUSETTS, ASSIGNOR TO THE HOLTZER-CABOT ELECTRIC COMPANY, OF ROXBURY, MASSACHUSETTS, A CORPORATION OF MASSACHUSETTS

HOSPITAL SWITCH

Application filed April 7, 1928. Serial No. 268,271.

The present invention relates to signaling devices, and more particularly to signaling devices of the type useful in hospital call systems.

5 The object of the present invention is to reorganize and improve signaling devices of this general nature and to this end the invention consists in the signaling device herein-after described and particularly defined in 10 the claims.

In the accompanying drawings illustrating the preferred form of the invention, Fig. 1 is a front elevation of the flush wall receptacle with the plug switch shown in dot and dash lines; Fig. 2 is a rear view of the switch; Fig. 3 is a sectional elevation of the switch on line 3—3 of Fig. 4; Fig. 4 is a front elevation of the switch with the cover partially broken away indicating the switch in "off" 15 position; Fig. 5 is a view similar to Fig. 4 with the switch in "on" position including a partial section on line 5—5 of Fig. 7; Fig. 6 is a section on line 6—6 of Fig. 4; Fig. 7 is a section on line 7—7 of Fig. 5; and Fig. 8 20 is a detail view of the actuating bulb.

The illustrated embodiment of the invention comprises a signaling device for a hospital call system and includes a wall box 10 having a flush wall receptacle 12 provided 25 with four split sockets 14, 16, 18 and 20 to receive the corresponding plugs of a switch box 22. The switch box 22 is operated by remote control means consisting of a tube 24 connecting the switch box and a com- 30 pressible bulb 26, which latter is kept at the bedside of the patient. To permit separable connection of the switch box 22 and the flush receptacle 12, the switch box has in the back four protruding plugs 28, 30, 32 and 34 to 35 be received respectively in the receptacle sockets 14, 16, 18 and 20. As shown in Figs. 1 and 2, the sockets and plugs are asymmetrically arranged so that the switch box cannot be improperly connected to the receptacle. The rear of the receptacle is mounted 40 in a wall outlet box and the signaling wires are connected to the contact sockets in the usual way. The contact socket 14 is a main current supply socket and the sockets 16 and 45 18 are connected with wires leading to two

separate main signal circuits and the socket 20 connects with a momentary audible signal, such as a buzzer. When the switch is in "off" position, there is no electrical connection between the contact 14 and any of the 55 other contacts, but when a call is to be made, electrical connections are established from the contact 14 to each of the contacts 16 and 18 and these connections are maintained until the device is reset by the answering nurse. 60 A momentary connection is also established between the contact 14 and the contact 20 to give a short audible signal. To actuate the call system as above described the switch box is constructed in the following manner. 65 It comprises an insulating casing to which a front cover 36 is attached, the four contact plugs being molded in the base or rear face of the casing. The main signal plugs 30 and 32 are diagonally opposed and terminate in 70 switch contacts 38 and 40 which protrude within the casing slightly beyond the base of the switch box. Centrally disposed between the diagonal plugs 30 and 32 is a post or bolt 42 which extends from into the casing, being secured in place by a nut 44. A rotatable switch bar 46 is mounted on the bolt and a torsion spring 48 which surrounds the bolt tends to turn the switch bar into the position shown in Fig. 5 where it bridges the protruding contacts 38 and 40. The ends of the torsion spring are secured to a projection 50 on the switch arm and to a nut 52 secured on the end of the bolt 42. A conducting strip 54 which is recessed in the base of the 75 switch box, connects the main supply plug 28 with the bolt 42 so that when the switch arm turns into the position shown in Fig. 5, an electrical connection is established from the receptacle socket 14 through the plug 28 and the switch arm 46 to each of the main signal plugs 30 and 32 and their corresponding receptacle contacts 16 and 18. The switch arm is normally retained in "off" position by means of a metal catch 56 projecting above the inner surface of the base. To 80 operate the switch the lower end of the switch arm 46 is raised above the catch 56, thereby permitting the torsion spring to turn the arm into "on" position. The spring is 85 90 95 100

also a compression spring, in order to hold the arm beside the catch in "off" position and against the contacts in "on" position. The arm is mounted with sufficient looseness on 5 the bolt to permit rocking thereof on the post to raise its lower end above the projection 56, a tight contact between the bolt and the switch arm being unnecessary, because the current is conducted to the switch arm 10 through the torsion spring. .

The actuating means for the switch arm will now be described. The base of the switch box is recessed at 58 to form a compression chamber and this chamber is closed 15 by a flexible diaphragm 60 which is held in place by a ring 62 secured to the base by screws. The switch holding projection 56 is formed integrally with the ring 62. As shown in Fig. 6, the ring 62 and the dia- 20 phragm 60 are received in an annular de- pression 63 surrounding the compression chamber and the catch 56 protrudes slightly above the wall of the depression. A tube 64 is molded in the bottom of the switch box 25 and communicates with the compression chamber, this tube being connected with the flexible tube 24 which leads to the bulb 26. A metal disc 66 of less diameter than the ring 56 overlies the diaphragm 60 and is sup- 30 ported by a thin flexible metal strip 67 which is secured under the nut 44 of the main center bolt 42. The disc 66 lies immediately under the end of the switch arm 46 so that when the bulb 26 is compressed, the dia- 35 phragm is raised and the switch arm is lifted over the projection 56, thus permitting it to turn and engage the contacts 38 and 40. The movement of the switch to "on" position is limited by a forwardly extended bent por- 40 tion 68 of the switch arm which projects through a slot 70 of the cover. This projec- 45 tion 68 also serves as a resetting means to return the switch to the position illustrated in Fig. 4.

45 The movement of the diaphragm upon compression of the bulb 26 is also employed to energize a momentary signal circuit which is connected to the socket 20. To this end, the shank of the plug 34 extends 50 through the base of the switch box and a wire 72 is connected to the plug 34 by means of a nut 74 which is threaded onto the shank of the plug. The other end of the wire 72 is connected with a conducting strip 76 which 55 extends transversely across the bottom of the switch box and is raised slightly above the base, being supported on bushings 78. The strip 76 has a contact projection 80 extending over the flexible strip 66. When the bulb 60 is compressed, therefore, the expansion of the diaphragm causes the flexible strip 66 to en- 65 gage with the projection 80 and thereby to close the momentary signal circuit. Upon release of the pressure in the bulb 26, the diaphragm collapses and the audible signal

circuit is broken. However, the switch arm 46 remains in the position shown in Fig. 5, maintaining the main signal circuits closed until the call is answered and the arm is reset.

70 In use as a hospital call system, the main circuit sockets 16 and 18 may be associated with visible signals of any desired form. Thus, the main signal contact 16 may connect with a central annunciator and the socket 18 with a lamp over the door of the patient's room. When the switch is in "on" 75 position, these main signal circuits are continuously energized until the switch is reset. The momentary signal contact which connects into a momentary signal circuit 80 through the receptacle socket 20 is employed to energize a buzzer or other temporary signal. Inasmuch as the purpose of this signal is merely to attract attention to the operation of the annunciator, it is required to be only 85 temporary. The momentary signal, therefore, operates when the bulb is compressed and stops when the bulb is released.

90 Although the invention in its preferred form has been illustrated and described, it is understood that the invention is not limited to such preferred construction. For example, the switch may be operated by other remote control means than a compressible bulb. Moreover, the term "plug" as used in 95 the claims is inclusive of any contact-making means, such as sockets or plug and socket connections.

100 Having thus described the invention, what is claimed is:

1. A signaling device having, in combination, a rotatable switch lever, a signal circuit contact, a catch normally holding the switch lever in "off" position and out of engagement with the signal circuit contact, a torsion spring tending to turn the switch lever into engagement with the contact, a flexible diaphragm cooperating with the switch lever and adapted to release the switch lever from the catch, and manually operated means for expanding the dia- 110 phragm.

2. A signaling device having, in combination, a rotatable switch arm, a contact adapted to be engaged by the switch arm, a catch for holding the switch arm in "off" position out of engagement with the contact, a torsion and compression spring acting to hold the switch arm against the catch when in "off" position and to press the switch lever against the contact in "on" position, and also to rotate the switch arm into engagement with the contact when released from the catch, and remote control means for releasing the switch arm from the catch. 120

3. A signaling device having, in combination, a rotatable switch arm, a post on which the arm is loosely mounted to permit rotative and rocking movements, a contact adapted to be engaged by the switch arm, a latch 130

- normally holding the switch arm in "off" position, a compression and torsion spring to press axially of the post against the arm to hold the arm in latched position and tending to rotate the arm into contact engaging position, and manually controlled means for rocking the arm out of engagement with the latch to permit it to be rotated into engagement with the contact. 5
- 10 4. A signaling device having, in combination, a rotatable switch arm, a post on which the arm is loosely mounted to permit rotative and rocking movements, a contact adapted to be engaged by the switch arm, a latch normally holding the switch arm in "off" position, a compression and torsion spring to press axially of the post against the arm to hold the arm in latched position and tending to rotate the arm into contact engaging position, the spring forming conducting means to conduct current to the arm, and manually controlled means for rocking the arm out of engagement with the latch to permit it to be rotated into engagement with the contact. 15
- 20 5. A signaling device having, in combination, a rotatable switch arm, a post on which the arm is loosely mounted to permit rotative and rocking movements, a contact adapted to be engaged by the switch arm, a latch normally holding the switch arm in "off" position, a compression and torsion spring to press axially of the post against the arm to hold the arm in latched position and tending to rotate the arm into contact engaging position, a release including a flexible diaphragm adapted to rock the arm out of engagement with the latch, and a manually controlled bulb for expanding the diaphragm. 25
- 30 6. A signaling device having, in combination, a rotatable switch arm, a post on which the arm is loosely mounted to permit rotative and rocking movements, a contact adapted to be engaged by the switch arm, a latch normally holding the switch arm in "off" position, a compression and torsion spring to press axially of the post against the arm to hold the arm in latched position and tending to rotate the arm into contact engaging position, a release including a flexible diaphragm adapted to rock the arm out of engagement with the latch, and a manually controlled bulb for expanding the diaphragm. 35
- 40 7. A signaling device having, in combination, a rotatable switch arm, a post on which the arm is loosely mounted to permit rotative and rocking movements, a contact adapted to be engaged by the switch arm, a latch normally holding the switch arm in "off" position, a compression and torsion spring to press axially of the post against the arm to hold the arm in latched position and tending to rotate the arm into contact engaging position, the spring forming conducting means to conduct current to the arm, a release including a flexible diaphragm adapted to rock the arm out of engagement with the latch, and a manually controlled bulb for expanding the diaphragm. 45
- 50 8. A signaling device having, in combination, a rotatable switch arm, a post on which the arm is loosely mounted to permit rotative and rocking movements, a contact adapted to be engaged by the switch arm, a latch normally holding the switch arm in "off" position, a compression and torsion spring to press axially of the post against the arm to hold the arm in latched position and tending to rotate the arm into contact engaging position, a release including a flexible diaphragm adapted to rock the arm out of engagement with the latch, a manually controlled bulb for expanding the diaphragm, and momentary signal contacts including a contact carried by the diaphragm and a stationary contact adapted to be engaged therewith. 55
- 60 9. A hospital switch having, in combination, a visible signal connection, an audible signal connection, patient controlled means for operating the two signal connections on the first operation of such patient controlled means and for operating the audible signal connections on each subsequent operation of the patient controlled means. 65
- 70 10. A hospital switch having, in combination, a visible signal connection, means for actuating it, a latch for holding it against actuation, an audible signal connection, patient controlled means for operating the two signal connections by releasing the latch for the visible signal connection and operating the audible signal connection so that on the first operation of the patient controlled means both signals will be given, and upon subsequent operations of the patient controlled means the audible signal only will be given. 75
